UNITED STATES PATENT OFFICE

100,200

DESIGN FOR A FISH BOWL

Samuel J. Carnes, Camden, Ark.

Application May 22, 1936, Serial No. 62,764

Term of patent 3½ years

To all whom it may concern:

Be it known that I, Samuel J. Carnes, a citizen of the United States of America and a resident of Camden, in the county of Ouachita and State of Arkansas, have invented a new, original, and ornamental Design for a Fish Bowl, of which the following is a specification, reference being had to the accompanying drawing, forming part hereof, in which;

Fig. 1 is a front elevation of a fish bowl, showing my new design.

Fig. 2 is a side elevation of the same.

Fig. 3 is a plan view of the same.

The dominant feature of my design resides in the portions shown in full lines.

I claim:

The ornamental design for a fish bowl, as shown and described.

In testimony whereof, I affix my signature.

SAMUEL J. CARNES.
